(57) **CLAIM**

I claim the ornamental design for a moisture absorbing pad, as shown and described.

DESCRIPTION

FIG. 1 is a perspective view of a moisture absorbing pad, showing my new design with an aperture thereof in a slightly open position;

FIG. 2 is a front elevational view of FIG. 1, the rear elevational view being a mirror image thereof;

FIG. 3 is a left-side elevational view of FIG. 1, the right-side elevational view being a mirror image thereof;

FIG. 4 is a top plan view of FIG. 1;

FIG. 5 is a bottom plan view of FIG. 1; and,

FIG. 6 is an exploded perspective view thereof.
